UNITED STATES PATENT OFFICE.

WILLIAM R. SMITH, OF BOSTON, MASSACHUSETTS, ASSIGNOR OF ONE-HALF
TO JOHN D. LARKIN, OF BUFFALO, NEW YORK.

PROCESS OF MAKING PATENT-LEATHER.

SPECIFICATION forming part of Letters Patent No. 732,129, dated June 30, 1903.

Application filed November 1, 1902. Serial No. 129,659. (No specimens.)

To all whom it may concern:

Be it known that I, WILLIAM R. SMITH, of Boston, in the county of Suffolk and State of Massachusetts, have invented certain new and useful Improvements in Processes of Making Patent-Leather, &c., of which the following is a specification.

This invention relates to the process of forming on one side of a piece of leather or other material a glossy coating, which is formed by applying a suitable composition to the leather and subjecting the coated leather to a sufficient degree of heat to vulcanize or harden the said coating, the product being the ordinary and well-known patent-leather of commerce. The degree of heat required to vulcanize the coating is such as to injuriously affect the leather, rendering the same brittle, so that the finished leather is liable to crack, especially when formed into curved articles, such as parts of boot and shoe uppers.

My invention has for its object to provide for the protection of the leather during the heating operation, so that the leather instead of being rendered brittle will retain its natural strength and pliability.

The invention consists in the improvements which I will now proceed to describe and claim.

Of the accompanying drawings, forming a part of this specification, Figure 1 represents a perspective view of an appliance used in practicing my hereinafter-described improvement. Fig. 2 represents a section on line 2-2 of Fig. 1. Fig. 3 represents a sectional view showing a modification of the device represented in Figs. 1 and 2.

a represents the sheet or piece of leather coated on one side, the coating being of any suitable nature adapted to be fixed and rendered hard and glossy by heat. In practice the sheet of leather after being coated is placed in an oven, where it is allowed to remain until the coating has been vulcanized or rendered firm.

In carrying out my invention I place the back or uncoated side of the leather in con-

tact with a protecting-bed, which is adapted to prevent injurious action of the heat upon the leather. In Figs. 1 and 2 I show a bed composed of a hollow chamber having means for the admission and exit of a current of air and internal means for circulating the air. *b* represents the chamber, which has an air-inlet pipe *c*, an air-outlet pipe *d*, and semipartitions or baffle-plates *e* *e* *e*, arranged to cause the air to pass in a sinuous course through the chamber, as indicated by arrows in Fig. 1, which shows a part of the chamber broken away. The sheet *a* of leather is placed upon the top of the chamber and may be suitably secured thereto by suitable means, such as by cords *f* *f*, engaging with hooks or studs *g* *g*, affixed to the top of the chamber. The chamber *b* is to be inserted in the vulcanizing or curing oven, the latter having provisions for the projection of the air-pipes *c* and *d* outside of the oven, so that the current of cool air may be forced through the chamber through the pipe *c*, the air heating the chamber escaping from the oven through the pipe *d*. I find that coated leather subjected to heat while supported by the top in the chamber *b* is not injured to any appreciable extent by the heat.

In Fig. 3 I show a bed composed of a sheet *b'* of asbestos supported by a suitable rigid base or holder *b''*. This bed is to be inserted in the oven with the sheet of leather placed upon the asbestos, the latter preventing the heat from being conducted to the under surface of the leather.

I do not limit myself to the described means for carrying out my invention and may use any other suitable means for protecting the back or under side of the piece of prepared leather while the coating on the front side of the piece is being vulcanized or cured.

It is obvious that cotton cloth and other materials may be treated in the manner above described. Hence my invention is not limited to so-called "patent-leather."

I claim—

1. That improvement in the art or process of coating leather and other materials, which

consists in protecting the back side of the piece of prepared material from heat while the coating on the front side of the piece is being vulcanized.

- 5 2. That improvement in the art or process of coating leather and other materials, which consists in conducting heat away from the back side of the piece of prepared material

while the coating on the front side of the piece is being vulcanized.

In testimony whereof I have affixed my signature in presence of two witnesses.

WILLIAM R. SMITH.
